CLAIM

The ornamental design for an ergonomic bath pillow as shown and described.

DESCRIPTION

FIG. 1 is a top front right side perspective view of an ergonomic bath pillow in accordance with the present design;

FIG. 2 is a bottom rear left side perspective view thereof; FIG. 3 is a bottom front right side perspective view thereof;

FIG. 4 is a top rear left side perspective view thereof;

FIG. 5 is a front view thereof;

FIG. 6 is a rear view thereof;

FIG. 7 is a left view thereof;

FIG. 8 is a right view thereof;

FIG. 9 is a top view thereof;

FIG. 10 is a bottom view thereof;

FIG. 11 is a top front right side perspective view of an ergonomic bath pillow according to another implementation;

FIG. 12 is a bottom rear left side perspective view thereof;

FIG. 13 is a bottom front right side perspective view thereof;

FIG. 14 is a top rear left side perspective view thereof;

FIG. 15 is a front view thereof;

FIG. 16 is a rear view thereof;

FIG. 17 is a left view thereof;

FIG. 18 is a right view thereof;

FIG. 19 is a top view thereof; and,

FIG. 20 is a bottom view thereof.

The broken lines present in the figures depict portions of the ergonomic bath pillow that form no part of the claimed design.
